UNITED STATES PATENT OFFICE.

ALEXANDRE DE BEAUMONT, OF CAMDEN, NEW JERSEY, AND SAMUEL SNELLENBURG, OF PHILADELPHIA, PENNSYLVANIA; SAID SNELLENBURG ASSIGNOR, BY MESNE ASSIGNMENTS, TO THOMAS B. HARNED, OF CAMDEN, NEW JERSEY.

FEED MECHANISM FOR SEWING-MACHINES.

SPECIFICATION forming part of Letters Patent No. 352,231, dated November 9, 1886.

Application filed October 2, 1885. Serial No. 178,811. (No model.)

To all whom it may concern:

Be it known that we, ALEXANDRE DE BEAUMONT, a citizen of the United States, residing in Camden, in the State of New Jersey, and 5 SAMUEL SNELLENBURG, likewise a citizen of the United States, residing in the city and county of Philadelphia, and State of Pennsylvania, have invented certain new and useful Improvements in Feed Mechanisms for Sewing-Machines, of which the following is a specification.

Our invention relates both to the feed mechanism and to the presser-feet of sewing-machines; and it relates especially to a presser-foot invented by us, and of such construction as to not only subserve its purpose of being a presser-foot, but also to co-operate with the feed proper in occasioning the feed of the fabric upon the bed-plate, the result of the operation of the device being that the upper of two pieces of fabric being stitched together is not creased or crimped up, but is, while in a perfectly smooth and flat condition, united to the under piece.

25 The improvements in sewing-machine feeds and presser-feet invented by us and above referred to constitute the subject-matter of an application, Serial No. 178,503, for patent filed by us in the United States Patent Office the 30 29th day of September, 1885.

The object of our invention is to provide an attachment which can be applied to any sewing-machine, and which will permit of the ready adjustment of the machine for feeding 35 in any desired direction.

Apparatus embodying our invention is represented in the accompanying drawings, and described in this specification, the particular subject-matter claimed as novel being herein- 40 after definitely specified.

In the drawings, Figure 1 is a front elevation of a device conveniently embodying our improvements. Fig. 2 is a top plan view of the same, section being supposed through the 45 shank of the presser-foot and through the needle-bar in the plane of the dotted line x x of Fig. 1. Fig. 3 is a top plan view of the foot of the presser-foot, the hub of said presser-foot being in horizontal section, so as to show 50 the knife-edge of the spring-clip in engage-

ment with a notch in the adjusting-ring. Fig. 4 is a perspective view of the presser-foot, showing also a portion of the adjusting-ring. Fig. 5 is a rear elevational view of the presser-foot, the view being designed to illustrate the 55 embrace of the clip against the rear face of the hub of the presser-foot. Fig. 6 is a perspective view of the spring-clip removed from the presser-foot.

For an exact understanding of our improvements it will be necessary also to describe the features which constitute a part of our other invention, hereinbefore referred to.

In the drawings, A is a portion of the head of the overhanging arm of the machine-frame. 60 B is the bed-plate, b an ordinary four-motion or other reciprocating feed, and C is the needle-bar, which is conveniently provided with a collar or other projection, c.

D is the shank of the presser-foot. 70 E is the presser-foot, e the foot thereof, and e^x the overhanging head thereof. The presser-foot is pivotally mounted upon what we term an "adjusting-ring," F, which is a fixed horizontally-disposed ring of metal connected with 75 and carried by the shank of the presser-foot. The presser-foot is so connected with the said ring, conveniently by means of a hub, e^s , as to be capable of being swept around the circumference thereof while at any point where it 80 happens to rest, being yet capable of a rocking movement with respect to said ring. The overhanging head e^x of the presser-foot is provided with an annular lip, e^2 , through which the needle-bar and the collar thereupon in the 85 reciprocation of the bar pass.

e^3 is a vertical flange erected from the lip e^2 , and e^4 is an inclined plane adjustably connected with respect to both the annular lip and the vertical flange last mentioned by the set-screw 90 e^5 . In the rising movement of the needle-bar the collar thereon encounters the inclined plane, and by said encounter deflects the entire presser-foot about its hub as a pivot, so as to occasion the movement of the foot of the 95 presser-foot in the direction of the arrow in Fig. 1 and in conjunction with the bed-plate feed.

It may be here explained that the feature of a combined presser-foot and feed, broadly 100

as such, is that which we have described and claimed in our application above referred to.

In the present case the improvement resides in mounting a presser-foot of the above character and mode of operation upon such a device as the adjusting-ring herein set forth, whereby the presser-foot, as an entirety, is adapted to be adjusted so as to operate to feed in any desired direction.

10 In order, in the case of our present improvements, after the descent of the needle-bar, to secure the re-deflection of the presser-foot to its normal position, or that represented in Fig. 1, a spiral spring, G, is provided and connected 15 with the presser-foot at its one extremity and at its opposite extremity with the adjusting-ring, it being for convenience coiled about said adjusting-ring. This spring serves to effect the return desired. When the presser-20 foot as an entirety is shifted upon the ring, the extremity of the spring, which is adapted to be connected with the ring—for instance, by being passed through holes f in the ring—is withdrawn from any particular hole and engaged with any other.

In order to secure the fixed retention of the presser-foot with respect to circumferential movement of position upon the adjusting-ring, we have provided a spring-clip, H, which is 30 connected with the overhanging arm of the presser-foot, and adapted by means of a knife-edge, h, connected with it, to be engaged with any one of a series of notches, f^x, formed in the adjusting-ring. The hub e^o of the presser-35 foot is slotted through, as at e^l, Fig. 4, to permit of the entrance of the knife-edge of the spring-clip into a notch, and of its continued engagement therein, notwithstanding the continued vibratory movement of the presser-foot 40 as an entirety. When it is desired to shift the presser-foot upon the ring, the spring-clip is simply raised or lifted up until its knife-edge is disengaged from the notch in which it happens to be engaged.

45 The entire contrivance of the spring-clip is simply one of convenience, and many other contrivances for retaining the presser-foot in a given position upon the ring may be, with perhaps equal advantage, resorted to in its 50 stead.

Such being a description of a form of apparatus conveniently embodying our improvements, we may say that we do not herein claim or seek to cover the invention of a pivoted or rocking presser adapted to act jointly 55 as a presser-foot and feed, and to be actuated by the movements of the needle-bar, our present invention being confined to the mounting of such a rocking presser-foot in such manner 60 as to occasion its operation for feeding in any desired direction.

The operation of the device has already been sufficiently indicated; but it is proper to add that when it is desired to employ the device 65 to feed continuously in the direction of the movement of the bed-plate feed the device is in operation placed in the position rep-

resented in Fig. 1, in which position the feed b is also employed. When, however, it is desired to feed in a direction that would be antagonistic to the operation of the said table-feed, the latter is thrown out of action and the presser-foot feed alone operated. It is proper for us also to state that while in most instances we prefer to have the under surfaces 75 of the foot of the presser-foot provided with teeth or serrations, or roughened, yet the foot will operate when its under foot is perfectly smooth.

Having thus described our invention, we claim—

1. The combination, in a sewing-machine, of a pivoted or rocking presser-foot, a needle-bar adapted to engage therewith and occasion the rocking of said foot, and a ring or rod secured to and carried by the presser-bar, and upon which said presser-foot is mounted for circumferential adjustment, substantially as set forth.

2. The combination, in a sewing-machine, of a pivoted or rocking presser-foot, a needle-bar adapted to engage therewith and occasion the rocking of said foot, a ring or rod secured to and carried by the presser-bar, and upon which said presser-foot is mounted for circumferential adjustment, and a spring connected with both adjusting-ring and presser-foot, substantially as set forth.

3. The combination, in a sewing-machine, of a pivoted or rocking presser-foot, a needle-bar adapted to engage therewith and occasion the rocking of said foot, a ring or rod secured to and carried by the presser-bar, and upon which said presser-foot is mounted for circumferential adjustment, a spring connected with both adjusting-ring and presser-foot, and means for maintaining the presser-foot in given positions upon the ring, substantially as set forth.

4. As a device for maintaining the presser-foot in given positions upon the adjusting-ring, the combination of the adjusting-ring provided with notches, the presser-foot adapted to rock thereupon, and a spring-clip applied to the presser-foot and adapted to engage with said notches, substantially as set forth.

5. The combination, in a sewing-machine, of a pivoted or rocking presser-foot, a needle-bar adapted to engage therewith and occasion the rocking of said foot, a ring or rod secured to and carried by the presser-bar, and upon which said presser-foot is mounted for circumferential adjustment, and a bed-plate feed operating in the plane of the bed-plate, substantially as set forth.

In testimony whereof we have hereunto signed our names this 24th day of September, A. D. 1885.

ALEXANDRE DE BEAUMONT.
SAMUEL SNELLENBURG.

In presence of—

W. C. STRAWBRIDGE,
J. BONSALE TAYLOR.
